UNITED STATES PATENT OFFICE.

CHARLES W. NYE, OF MINNEAPOLIS, MINNESOTA, ASSIGNOR TO THE MINNESOTA STOVE COMPANY, A CORPORATION OF MINNESOTA.

CONVERTIBLE OVEN FOR RANGES.

1,309,100.

Specification of Letters Patent.

Patented July 8, 1919.

Application filed April 19, 1918. Serial No. 229,514.

To all whom it may concern:

Be it known that I, CHARLES W. NYE, a citizen of the United States, residing at Minneapolis, in the county of Hennepin and 5 State of Minnesota, have invented certain new and useful Improvements in Convertible Ovens for Ranges, of which the following is a specification.

My invention relates to convertible ovens 10 for ranges and has for its object to provide an oven which can be readily changed so as to adapt it for use with ranges either when fuel such as coal or wood is used or when fuel of a different character such as gas is 15 used. A further object is to provide an oven of this character which can be changed to adapt it for one use or the other in the minimum of time and with a minimum of effort.

20 The full objects and advantages of my invention will appear in connection with the detailed description thereof and are particularly pointed out in the claims.

Referring to the accompanying drawings, 25 which illustrate the application of my invention in one of its forms,—

Figure 1 is an end view of a range showing the oven in section. Fig. 2 is a front view of the oven portion of the range showing the oven door open. Fig. 3 is a view similar to Fig. 1 but showing the oven having certain changes made to adapt it for using gas as a fuel. Fig. 4 is a top plan view of a movable member which is used 30 when the oven is heated by gas. Fig. 5 is a detail view on the line 5—5 of Fig. 2, showing the flue and controlling door for the exit of spent gases. Fig. 6 is a view of the disconnectible gas supply for the 35 burner. Fig. 7 is a face view of the air controlling inlets leading to the gas burner.

In the drawings 10 indicates the fire chamber end of the range adapted to use solid fuel such as wood or coal. Since this 40 portion of the range is of the usual construction it is not necessary to illustrate and describe the same in detail. 12 indicates the oven and gas burner end of the range to which my invention is applied. 14 designates the customary oven door hinged to the 45 front wall of the range at 16 and shown in open position in Figs. 1 and 2 and in closed position in Fig. 3. The end walls of the oven are provided with the usual slide-

ways 18 for the grid or shelf 20. In order 55 that the oven may be heated by gas, I provide a slidable member which is entirely removed from the oven when solid fuel is used, but which is placed in the bottom of the oven and slid rearwardly when gas is 60 used. This slidable member comprises a base plate 20 having upwardly-extending lugs or straps 22 which hold the burner 24 in place, and extending upwardly from the burner are lugs or straps 26 which secure a 65 baffle plate 28 in place. The baffle plate is of less length and width than the oven and is surrounded by a grid portion 30 at the ends. The peripheral portion of the grid extends around the front of the baffle plate. 70 This construction provides for proper circulation of the heated air in the oven. The rear end of the burner is integral with a pipe section 32 at right angles thereto, which in turn is bent at a right angle to form a 75 pipe section 34 which is offset from the burner. The slidable member is adapted to be slid on the bottom of the oven and over the cold air flue 36. The rear wall of the oven is provided with two hinged doors 38 80 and 40 secured to a rotatable rod 41 mounted in the rear wall. When the slidable member is pushed toward the rear of the oven, the end of the pipe section 34 strikes the door 40, lifting the same and also lifting the 85 door 38. The latter door controls an opening to the spent gas flue 42, as best shown in Fig. 5. The rear end of the pipe 34 is enlarged and formed with a wall 44, as best 90 shown in Figs. 6 and 7, which has a central opening 46 and concentric slots 48 which may be made to register more or less with concentric slots 50 in a disk 52 adjustably connected to the wall 44 by set screws 54. The disk 52 has an opening forming a 95 continuation of the opening 46, and this opening is coned so as to form a rearwardly-flaring passageway to receive the coned end 56 of a branch pipe 58 leading from the main gas supply pipe 60 which also supplies 100 the burners at the top of the range. The branch pipe 58 is controlled by a valve 62 operated by a rod 64 having a handle 66 at its front end within easy reach at the front of the range.

The operation and advantages of my invention will be readily understood from the foregoing description. When the sliding

member is removed from the oven, the doors 38 and 40 drop into place by gravity and close the openings which they control, so that the oven may be used as an ordinary 5 oven in connection with the fire chamber 10. When it is desired to heat the oven by gas, the oven door 14 is opened and the slidable member previously referred to is slid along the bottom of the oven until the coned opening 46 fits snugly over the coned end 56 of the gas supply pipe, which acts as a guide for that purpose. During this operation both of the doors 38 and 40 are opened by engagement of the pipe 34 with the door 40. 10 Proper positioning is insured since it is impossible to entirely close the door 14 before the slidable member is moved to its extreme rearward position. It will thus be apparent that I provide a convertible oven which can 15 be easily and quickly changed from one type of fuel utilization to another. Although the pipe section 34 is guided in its rearward movement, as previously stated, by the coned end 56 of the supply pipe which 20 enters the coned opening 46, I prefer to also provide an additional guide consisting of the annular member 68 which is secured to the range so as to be concentrically spaced from the end 56. This member is shown in 25 Fig. 6 as coned in its inner circumference in order that the enlarged end of the pipe section 34 may slide thereon.

I claim:

1. A convertible oven comprising a gas 35 admission door, a spent gas outlet door, both of said doors being hinged to the rear wall of the oven, a gas burner adapted to be slid into the bottom of the oven when the main door at the front thereof is open, and means 40 whereby both of said rear doors are opened by sliding movement of said burner.

2. A convertible oven comprising a gas admission door, a spent gas outlet door, both of said doors being hinged to the rear wall 45 of the oven, a gas burner and attached baffle plate adapted to be slid into the bottom of the oven when the main door at the front thereof is opened, means whereby both of said rear doors are opened by sliding movement of said burner, a gas supply pipe having its end located rearwardly of said gas admission door, and means whereby said burner and said supply pipe are caused to

snugly engage each other when said burner is slid into place.

55

3. A convertible oven comprising a gas admission door, a spent gas outlet door, a rod rotatably mounted in the rear wall of the oven, both of said doors being secured to said rod, a burner adapted to be slid into 60 the bottom of the oven when the main door at the front thereof is opened, the rear end of said burner being positioned to engage said gas admission door to open the same and also open said gas outlet door, the gas 65 supply pipe having its delivery end in line with said rear burner end, and means whereby said pipe section and said supply pipe are caused to snugly engage each other by sliding movement.

70

4. A convertible oven comprising a gas admission door, a spent gas outlet door, a rod rotatably mounted in the rear wall of the oven, both of said doors being secured to said rod, a burner adapted to be slid into 75 the bottom of the oven when the main door at the front thereof is open, a pipe section connected to the rear of said burner and positioned to engage said gas admission door and also open said gas outlet door, a gas supply pipe having its delivery end in line with said pipe section, and means whereby said pipe section and said supply pipe are caused to snugly engage each other by sliding movement.

80

5. A convertible oven comprising a gas admission door, a spent gas outlet door, a rod rotatably mounted in the rear wall of the oven, both of said doors being secured to said rod, a baffle plate, a burner attached to 90 said baffle plate, said burner and baffle plate being adapted to be slid into the bottom of the oven when the main door at the front thereof is open, an offset pipe section connected to the rear of said burner and positioned to engage said admission door to open the same and also open said outlet door, a gas supply pipe having its delivery end in line with said pipe section, and means whereby said pipe section and said supply pipe are 100 caused to snugly engage each other by sliding movement.

85

In testimony whereof I hereunto affix my signature.

CHARLES W. NYE.
